UNITED STATES PATENT OFFICE.

LOUIS P. D. YOST, OF CANTON, OHIO.

DESIGN FOR AN AIR-FURNACE.

SPECIFICATION forming part of Design No. 26,117, dated September 29, 1896.

Application filed August 13, 1896. Serial No. 602,814. Term of patent 14 years.

To all whom it may concern:

- Be it known that I, LOUIS P. D. YOST, a citizen of the United States, and a resident of Canton, county of Stark, State of Ohio, have invented and produced a new and useful Design for Hot-Air Furnaces, of which the following is a full, clear, and exact description, reference being had to the accompanying drawing, making part of this specification.
- 10 My invention relates to a new design for hot-air furnaces; and it consists of a furnace of the configuration and ornamentation shown in the accompanying drawing, in which the design is illustrated in perspective.
- 15 The leading features of the design are the ring-like base 1, having radiating from its central portion 2 curved arms 3, a cylindrical portion 4, having a flaring box-like section 5, a cylindrical section 6, having an annularly-arranged row of ribs 7 and a forwardly-projecting rectangular box portion 8, from which extends downwardly to the box-like section 5 a tubular portion 9, and from which extend

upwardly and rearwardly in a curved and diverging course two tubular portions, the dome-shaped section 11, having ribs 12 aligned with the ribs 7 and provided with a rectangular forwardly-projecting box-like section 13, a series of annularly-arranged and vertically-projecting cylindrical bodies 14, a cylindrical curved body 15 below the cylindrical bodies 14 and curved about the dome-shaped section 11, the rings 16 and 17, respectively, at the upper and lower ends of the cylindrical bodies 14, and the laterally-projected cylindrical body 18.

What I claim is—

The design for a hot-air furnace as herein shown and described.

In testimony whereof I have hereunto set my hand this 31st day of July, A. D. 1896.

LOUIS P. D. YOST.

Witnesses:

W. K. MILLER,
CHAS. M. BALL.
